UNITED STATES PATENT OFFICE

ELLIS H. BRIDGE, OF AKRON, OHIO, ASSIGNOR TO THE ELECTRIC STORAGE BATTERY COMPANY, OF PHILADELPHIA, PENNSYLVANIA, A CORPORATION OF NEW JERSEY

HYDROMETER SYRINGE

Application filed May 10, 1929. Serial No. 361,861.

My invention relates to hydrometer syringes particularly those adapted for use with storage batteries or for measuring the specific gravity of the cooling fluid of automobile 5 or other internal combustion engines.

The object of this invention is to produce an improved hydrometer syringe in which the liquid whose specific gravity is to be measured is always lifted to a fixed and constant level so as to allow free action of the float and to permit more ready reading of the hydrometer.

Another feature of my invention is that when the liquid, drawn into the barrel of the 15 hydrometer, has reached a fixed and constant level, which has been predetermined, the excess liquid is by-passed to the bulb.

Another feature of my invention is that the liquid does not come into contact with 20 the portions of the barrel of the hydrometer through which the readings are made so that these portions do not become obscured and therefore readings may be more accurately made.

25 A still further feature of my invention is that in my hydrometer the indicating markings may be located on the barrel of the hydrometer thus enabling a more accurate reading to be made than when the markings 30 are on the float as has heretofore been the common practice.

An additional feature of my invention is an hydrometer in which the bulb is in liquid contact with the liquid whose specific gravity 35 is being measured so that if the operator of the hydrometer retains manual hold on the bulb the vibrations or tremors of his hand will not cause vibrations or fluctuations of the liquid.

40 Yet another feature of my invention is to produce an hydrometer having the desirable features above mentioned which is nevertheless capable of functioning as a syringe for 45 the purpose of adding liquid to or removing liquid from the body of liquid whose specific gravity is being tested.

For a more complete disclosure of my invention reference may be had to the annexed drawings and specification at the end where-

of my invention will be specifically pointed out and claimed.

In the drawings,

Figure 1 represents a view partially in cross-section through my device. 55

Figure 2 is a cross-section showing a modified form of my device.

In the drawings there is shown an hydrometer syringe consisting of a hollow tubular barrel or casing 1 having a neck 2 of reduced 60 diameter extending therefrom. At the end of the neck 2 there may advantageously be located a flexible filling tube 3.

At the opposite end of the barrel 1 there is located a bulb 4 of flexible material. Between the bulb 4 and the barrel 1 there is located a stopper or plug 5 which serves to seal the barrel 1 from the bulb 4. Extending through the stopper 5 and down into the barrel 1 is a tube 6 which may advantageously 70 be made of hard rubber or other suitable material. Preferably, this tube is shaped so as to lie adjacent to one of the walls of the barrel or casing 1. Located within the barrel 1 is a float 7 of suitable diameter to ride in the 75 neck 2. The float 7 has a stem 8 of reduced diameter and is customarily so weighted as to float with the stem upright. It is customary, at present, to place indicating marks 9 on the stem of the float. I may prefer, 80 however, to place indicating marks 10 on the barrel 1 which may be composed, wholly or in part, of transparent or translucent material.

The operation of my device is as follows: 85 When it is desired to ascertain the specific gravity of a body of liquid the flexible tube 3 is inserted into the liquid and the bulb 4 squeezed or pressed upon so as to be contracted. The bulb 4 is then allowed to expand and fluid is drawn up into the barrel 1. A sufficient amount of liquid is drawn up into the barrel 1 until tube 6 contacts with the surface of the liquid. The suction of the bulb 4 then serves to draw the liquid through 90 the tube 6 up into the interior of the bulb. The upper part of the casing 1 therefore does not come into contact with the liquid so that this surface is not obscured thereby nor do 95 deposits of dirt form on the casing above the 100

fixed level. It is desirable that this surface be kept as clean as possible and that the usually clouded liquid should not obscure the stem of the float if the indicating marks are located on the stem of the float. It is necessary to look through this portion of the casing in order to view the indicating marks. If the indicating marks are located on the casing 1 it is, nevertheless, necessary to look through this surface to locate the position of the top of the float.

The tube 6 extends into the casing 1 a sufficient length so that the level predetermined for the liquid in the casing 1 is sufficiently low to allow free operation of the float in the casing. In other words, no matter how much of the stem 8 extends above the surface of the liquid it will not come into contact with the upper portion of the casing 1 or with the stopper 5. For this reason also it is desirable to locate the tube 6 adjacent to the side of the casing 1 so that it will not interfere with the operation of the float 7.

Figure 2 shows a modified form of my device in which the bulb 4 is attached to the barrel 1 just above the neck 2. It will be apparent that when the bulb 4 of this modification is contracted and allowed to expand the liquid will enter the barrel 1 and then enter the bulb 4, thus establishing a constant level near the bottom of the casing 1.

The described device produces a constant level in the liquid chamber and the only variation in respect to variation in density is the height of the hydrometer float in respect to the barrel so that it is possible to mark specific gravity readings directly upon the barrel, as indicated in Fig. 1, and to use the top of the hydrometer float as the indicator with respect to the marking on the barrel.

40 I claim:

1. An hydrometer syringe for visual indication of specific gravity comprising a transparent barrel having an inlet at one end into which a liquid may be drawn and having an opening at the other end, a float in the barrel, an elastic bulb mounted on said other end of the barrel, a perforated stopper in said opening at said other end of the barrel, and a tube communicating with the interior of the bulb through the stopper and extending into the barrel a sufficient distance so as to draw liquid into the barrel to a fixed level, liquid in excess of that required to fill the barrel to said level being drawn up into the tube, said float being adapted to be freely suspended in the barrel when the liquid is at said fixed level.

2. An hydrometer syringe for the visual indication of specific gravity comprising a transparent barrel, a float located in the barrel and visible through the barrel, said barrel having an inlet through which a liquid may be drawn into the barrel, and suction means associated with the barrel, said suc-

tion means having an inlet located at a point intermediate the ends of the barrel so that the suction means will draw liquid into the barrel to a fixed level at said point and liquid in excess of that required to fill the barrel to said level will be drawn into the suction means, said float being adapted to be freely suspended in the barrel when the liquid is at said fixed level.

3. An hydrometer syringe for the visual indication of specific gravity comprising a transparent barrel, a float located in the barrel and visible through the barrel, said barrel having an inlet through which a liquid may be drawn into the barrel, and suction means including an elastic bulb associated with the barrel, said suction means having an inlet located at a point intermediate the ends of the barrel so that the suction means will draw liquid into the barrel to a fixed level at said point and liquid in excess of that required to fill the barrel to said level will be drawn into the suction means, said float being adapted to be freely suspended in the barrel when the liquid is at said fixed level.

4. An hydrometer syringe for the visual indication of specific gravity comprising a transparent barrel, a float located in the barrel and visible through the barrel, said barrel having an inlet through which a liquid may be drawn into the barrel, and suction means associated with the barrel, said suction means having an inlet located at a point intermediate the ends of the barrel so that the suction means will draw liquid into the barrel to a fixed level at said point and liquid in excess of that required to fill the barrel to said level will be drawn into the suction means, said float being adapted to be freely suspended in the barrel when the liquid is at said fixed level, said barrel having indicia thereon above said fixed level whereby the specific gravity of a liquid may be determined by the position of the float respecting said indicia.
